DESIGN FOR A SCARF OR ANALOGOUS ARTICLE

Desider Friedman, New York, N. Y.

Application March 31, 1942, Serial No. 106,407

Term of patent 3½ years

To all whom it may concern:

Be it known that I, Desider Friedman, a citizen of no country, but have declared my intentions of becoming a citizen of the United States of America, residing in the city of New York and State of New York, have invented a new, original, and ornamental Design for a Scarf or Analogous Article, of which the following is a specification, reference being had to the accompanying drawing, forming part thereof, wherein the figure of the drawing is a plan view of a scarf or analogous article, showing my new design.

I claim:

The ornamental design for a scarf or analogous article, substantially as shown.

DESIDER FRIEDMAN.
